UNITED STATES PATENT OFFICE.

ROBERT WALSH, OF PITTSBURG, PENNSYLVANIA.

SMOKE-CONSUMING FURNACE.

SPECIFICATION forming part of Letters Patent No. 540,805, dated June 11, 1895.

Application filed June 7, 1894. Serial No. 513,779. (No model.)

To all whom it may concern:

Be it known that I, ROBERT WALSH, a citizen of the United States, residing at Pittsburgh, in the county of Allegheny and State of Pennsylvania, have invented or discovered a new and useful Improvement in Smoke-Consuming Furnaces, of which the following is a full, clear, and exact description, reference being had to the accompanying drawings, forming part of this specification, in which—

Figure 1 is a longitudinal vertical section of the furnace-chamber of a boiler-setting embodying my invention. Fig. 2 is a horizontal sectional view taken on the line II II of Fig. 1, illustrating the arrangement of the air inlet and heating chambers. Fig. 3 is a vertical cross-sectional view taken on the line III III of Fig. 1. Fig. 4 is a similar sectional view taken on the line IV IV of Fig. 1. Fig. 5 is a view similar to Fig. 4, illustrating a modified construction. Fig. 6 is a cross-sectional view of a furnace-setting, showing the manner of supporting the arches when the combustion-chamber is exceptionally wide. Fig. 7 is a detail view, on an enlarged scale, of my improved skewback. Fig. 8 illustrates the application of the skewback to a series of arches. Fig. 9 is a partial vertical section of an upright boiler furnished with a surrounding jacket, forming an air-heating space and a special construction of air-supplied baffle-wall. Fig. 10 is a cross-section of Fig. 9 on the line X X of Fig. 9.

Like symbols of reference refer to like parts throughout this specification.

My invention consists in an improvement in the construction of the combustion chamber of fuel burning furnaces, having for its object the perfect combustion of all the elements of the fuel, to the combined ends of securing the highest possible results as to heat from the fuel burned and the resultant absence of smoke and other objectionable products of combustion, together with certain features of novelty relating to the construction of the baffle wall arches, whereby I am enabled to construct such arches across a very wide space of combustion chamber without the use of supporting piers or other obstructions, thereby giving the entire area for the passage of the gases.

In the drawings I have shown my construc-

tion of combustion chamber as applied to an ordinary tubular boiler, but I am not limited to such construction, as it may with equal 55 readiness be applied to many other forms in which similar results are desired, as for instance puddling and heating furnaces and glass melting furnaces; garbage and domestic furnaces, stoves and grates, and to many 60 kinds where the nature of the construction is such as to admit of the conditions of my improvement being fulfilled.

In a prior patent granted to me February 27, 1894, I have illustrated a construction of 65 furnace having many of the features of my present invention, and it now consists of the same general arrangement of air heating passages and supply ports together with certain novel and valuable additional features of improvement, which I have found in practice to 70 be of great advantage in the operation of the furnace.

The special object of my present invention is to thoroughly mix the various quantities of 75 air entering through the openings 8 so that their temperature shall be as nearly uniform as possible when entering the different ports leading to the combustion chamber.

It also consists in a new arrangement of the 80 ports leading into the baffle wall; in a preferred construction of the top of the bridge wall, whereby it is sloped upward; in the manner of supporting the partition wall on arches over the bridge wall, and in an adjustable deflecting tile for controlling the quantity and direction of the flow of escaping gases.

A further modified construction of the arches is shown in Fig. 6, in which I illustrate 90 a novel method of supporting the two inner abutting ends of arches under a battery of two boilers, thus obviating the necessity of a center pier in the combustion chamber and giving the full width for free and unimpeded 95 passage of the gases, the arches being supported by an overhung, hollow, water-supplied skew-back. Shown in Fig. 8.

A further feature of improvement consists in the adaptation of my system of preheating 100 the air and supplying it to the combustion chamber of a vertical boiler, enabling me to secure equally good results as in the horizontal type.

Referring now to the drawings: 2 represents the front and back walls of a furnace, the side walls of which are formed of an inner and an outer wall 3 4 forming between them the passage 5. Beneath the floor of the back part of the furnace 6 is a series of flues or passages 7 provided with inlet openings 8 for the admission of air; and for the purpose of permitting the colder currents to mingle with the warmer air, due to some portions of the brickwork being hotter than others, the partitions *a a* and *3 3* are provided at intervals with openings *b* to facilitate such mixture as indicated by the arrows in Fig. 2. These openings may be made of sufficient number to insure free passage of the air, and their number, size, and location will be decided by the skilled furnace builder.

9 is the combustion chamber, below which are located the grate bars 10 and immediately back of the ends of the bars is the hollow bridge wall 11, constructed in like manner to the side walls and communicating with the passages therein and with the central ground passages 7. The bridge wall is made preferably with an upwardly and forwardly extending top *c* for the purpose of deflecting the gases of combustion up against the shell of the boiler, and it is supplied along its top with the ports 12 and in front immediately under the grate bars with the ports 13, through which the previously heated air passes to the interior of the combustion chamber.

35 At various heights throughout the combustion chamber are arranged rows of ports 14 communicating with the opening 5 in the side walls, the purpose of which is to distribute the heated air thoroughly throughout the entire area of the furnace, and to bring it into contact with the fire. The amount of air that is admitted into the openings 8 may be regulated by stoppers or dampers, which may be placed therein, and the doors in front are supplied with dampers 15 for a like purpose.

In Fig. 3 is illustrated an important feature of my present invention, showing the manner of dividing the area above the bridge wall and of supporting the partition wall 20 by means of the arches 19 19 and vertical piers 18 thereby providing a considerable space D above the top of the arches and below the tile *f* which space constitutes a pocket or receptacle into which the gases of combustion will escape and where they will receive an additional supply of hot air from the ports 14 after passing under the baffle wall 21. In practice I have found that the gases will undergo a reverberatory action in this space, as indicated by the arrows, after which they will pass out over the hollow bridge wall 11, receiving a fresh supply of hot air, sufficient to accomplish a perfect final combustion. In the chamber 6 is located an adjustable tile 22 bearing at its lower forward end against a stop 23 and resting on an arm 24 secured to the shaft 25, so that when the shaft is rotated

the tile may be raised or lowered to control the draft of the furnace, and to deflect the gases upward.

In Fig. 4 I have illustrated the method in which I introduce currents of previously heated air into the body of the baffle wall 21 from the wall passages 5. Running through the top of the baffle wall, from side to side in communication with the passages 5 is the port 26, having downwardly directed exit ports 27 leading into the chamber 9 directly over the grate bars. This arrangement of ports gives a good volume of air and is very easy to construct and effective in operation. The baffle wall also extends upwardly as high as the level of the tile *f* forming a reverberatory chamber G similar to the chamber D previously described and in which the gases, first thrown off from the fuel, circulate as indicated by the arrows, and receive an admixture of heated air from additional ports 14.

It will be understood that the chambers D and G are alike on each side of the center of the boiler, and in the case of a heating furnace or other similar furnace, where their area is not reduced as by the boiler, their capacity and effect will be much increased.

In Fig. 5 I have illustrated another manner of stepping the wall up on the inside which is sometimes necessary owing to reduced space and other causes. The effect is to reduce the capacity of the reverberatory chamber D but in other respects the construction and operation are the same.

I have found in practice that it is frequently necessary to construct a combustion chamber under a battery of two or more boilers and in such cases the width between the walls of the furnace is so great as to prevent a single arch being sprung across, and I have therefore designed the supporting skew-back illustrated in Figs. 6, 7, and 8, which may be used either in the baffle wall or the division wall above the bridge wall, or both. In the center between the abutting ends of the arches 19' is located the skew-back *S* made of cast iron and preferably hollow for the circulation of water to keep it cool and prevent burning out. An eye *s* is cast in and is engaged by a hook on the lower end of a supporting rod 28 which rod is firmly supported by attachment to beams 29 resting on the boiler shell or side walls. A circulation of water is maintained within the skew-back by the supply pipe 30 and exhaust pipe 31, and both these pipes are preferably embedded in the brickwork for the purpose of protecting them from the action of heat. This construction is very satisfactory and effective in practice, affording a substantial and durable support for the ends of the arches, allowing unimpeded passage of the gases, and, as illustrated in Fig. 8 a number of arches may be so supported to advantage within a single combustion chamber, their number not being limited, and the shape, size and number of the arches may be determined by the width of the combustion cham-

ber, number of boilers, &c. It is obvious that both the baffle wall arch and the partition arch above the bridge wall may be supported in this manner. In its application to an up-right boiler, the baffle wall will act, substantially the same as in a horizontal type, except that the baffle wall 21 alone is used, having the horizontal portion *r* and downwardly directed portion *t*, the usual ports 27, and passage 26' being in communication with the surrounding jacketed cavity 5', the shell of the boiler 3' forming the inner wall, and the jacket 4' the outer, which may be of sheet metal or brickwork or any other desirable or suitable material. A partition 32 is located centrally on opposite sides of the boiler, extending up to within a short distance of the top of the air chamber, giving a greatly increased circulation of the air, which finally escapes through openings 13' into the ash pit from whence it passes up through the grate bars.

Changes and modifications may be made in its construction by the skilled mechanic without departing from my invention, as for instance hollow metal or clay pipes may be introduced into the brickwork, for the air, in place of any of the ordinary passages or ports, and I desire it to be understood that in the broad meaning of the words "passage" and "port" I mean to include any and all such means, where their purpose is to serve as air conductors.

Having described my invention and in what manner it is constructed and operated, what I claim, and desire to secure by Letters Patent, is—

1. In a furnace, the combination of a combustion chamber 9, divided transversely by the air supplied arched baffle wall 21, air supply ports 14 and 27 in communication with air passages 5 in the side walls; with the hollow bridge wall 11 having an upwardly and forwardly extending top *C*, vertical piers 18, arches 19 and partition walls 20 filling the space between the arches 19 and the top tiles *f*, the hollow bridge wall being also in communication with air passages 5 in the side walls, and also with floor passages 7, substantially as shown and described. 50

2. In combination with a furnace, preliminary air heating supply passages in communication with the atmosphere, located beneath the floor of the furnace, divided by partition walls *a*, *a*, and 3, 3, inlet openings 8, cross passages *b* in walls *a* and 3, such passages *b* in walls *a* and *b* respectively being so located as not to be opposite each other, for the purpose of intermingling the currents of incoming air, substantially as shown and described. 60

In testimony whereof I have hereunto set my hand this 3d day of May, 1894.

ROBERT WALSH.
